UNITED STATES PATENT OFFICE.

JACOB SCHAFER, OF NEW YORK, N. Y., ASSIGNOR TO STAR CHANDELIER COMPANY, INC., OF NEW YORK, N. Y., A CORPORATION OF NEW YORK.

DESIGN FOR A CHANDELIER.

Application filed May 29, 1925. Serial No. 13,593. Term of patent $3\frac{1}{2}$ years.

To all whom it may concern:

Be it known that I, JACOB SCHAFER, a citizen of United States, residing in New York, Bronx County, city and State of New York, have invented a new, original, and ornamental Design for a Chandelier, of which the following is a specification, reference being had to the accompanying drawing, forming part thereof.

The figure shows a side elevational view partly in perspective, illustrating my design.

I claim:—

The ornamental design for a chandelier, as shown.

JACOB SCHAFER.
